United States Patent Office

Des. 200,846

Patented Apr. 13, 1965

200,846

SHOE

Norman E. Bovay, Seymour, Conn., assignor to United States Rubber Company, New York, N.Y., a corporation of New Jersey

Filed Sept. 24, 1964, Ser. No. 81,861

Term of patent 14 years

(Cl. D7—7)

FIG. 1 is a side elevational view of one side of the shoe;

FIG. 2 is a bottom plan view;

FIG. 3 is a side elevational view of the other side of the shoe; and

FIG. 4 is a fragmentary sectional view taken along line 4-4 in FIG. 3.

I claim:

The ornamental design for a shoe, substantially as shown.
